CLAIM

We claim the ornamental design for a footwear care machine, as shown and described.

DESCRIPTION

FIG. 1 is a right-side perspective view of a footwear care machine showing the new design; FIG. 2 is a front view thereof; FIG. 3 is a rear view thereof; FIG. 4 is a left-side elevation view thereof; FIG. 5 is a right-side elevation view thereof; FIG. 6 is a top plan view thereof; FIG. 7 is a bottom plan view thereof; FIG. 8 is a partial enlarged right side perspective view of the portion designated “8” in FIG. 1; and, FIG. 9 is a partial enlarged left side perspective view thereof. The dot-dot-dash broken lines shown in the figures are for the purpose of illustrating the detail markers for the enlarged detail views and form no part of the claimed design. The dash broken lines in the figures are for the purpose of illustrating portions of the footwear care machine and form no part of the claimed design.
